MOTORCYCLE TOTE BOX

Harold H. Larsen, Long Beach, and Robert E. Oehring,
Norwalk, Calif., assignors to Bates Industries, Inc.,
Long Beach, Calif.

Filed Mar. 14, 1974, Ser. No. 451,224

Term of patent 14 years

Int. Cl. D12—11

U.S. Cl. D12—158

FIG. 1

FIG. 2

FIG. 3

FIG. 6

FIG. 5

FIG. 1 is a perspective view of a motorcycle tote box showing our new design;

FIG. 2 is a front elevational view thereof;

FIG. 3 is a left side elevational view thereof; the right side being a mirror image of the left side shown herein;

FIG. 4 is a rear elevational view thereof;

FIG. 5 is a top plan view thereof; and

FIG. 6 is a bottom plan view thereof.

We claim:

The ornamental design for a motorcycle tote box, substantially as shown.
